UNITED STATES PATENT OFFICE.

WILLIAM H. WHARTON, OF PHILADELPHIA, PENNSYLVANIA, ASSIGNOR
OF ONE-HALF TO LEONARD E. LADD, OF SAME PLACE.

RETAINER FOR UMBRELLA OR PARASOL RUNNERS.

SPECIFICATION forming part of Letters Patent No. 366,801, dated July 19, 1887.

Application filed January 7, 1887. Serial No. 223,656. (No model.)

To all whom it may concern:

Be it known that I, WILLIAM H. WHARTON, a citizen of the United States, residing in the city and county of Philadelphia, State of Pennsylvania, have invented a new and useful Improvement in Retainers for Umbrella or Parasol Runners, which improvement is fully set forth in the following specification and accompanying drawings, in which—

10 Figure 1 represents a side elevation of a retainer for the runner of an umbrella or parasol embodying my invention, including a longitudinal section of a portion of the stick thereof. Fig. 2 represents an end view thereof.

15 Similar letters of reference indicate corresponding parts in the two figures.

My invention consists of a retainer for an umbrella or parasol runner, provided with means for securing the same to the stick without necessarily employing rivets or similar fastenings.

It also consists of means for limiting the outward motion of the head of the retainer.

Referring to the drawings, A represents the 25 retainer for the runner of an umbrella, consisting of the head A', shank B, back plate, C, spurs D E, and the stops F G, all formed together in the present case of a single piece of sheet metal or other suitable material, the 30 shank being separated from the plate C, whereby the former may move to and from the latter.

The head A' is at one end of the shank, and the latter is held at the opposite end by the 35 attachment with the plate C, whereby it is elastic in its nature, so as to yield when the head is pressed in and restore the same to its normal position for releasing or holding the runner, as the case may be, two retainers being employed, one for the runner when the umbrella is open, as shown in the drawings, and another for the runner when the umbrella is closed, the retainers being fitted in the stick in reversed positions.

40 The spur D projects from the plate C in the direction of the length of the same, and the spur E projects laterally therefrom, it being noticed that the spurs are at opposite ends of said plate.

45 In the back of the head A' is a slot, H, which has at the end of one of its walls the shoulder

or stop F, and projecting into said slot is the stop G, which is secured to the plate and has at its end a shoulder, G', which abuts against or interlocks with the shoulder F when the 55 head is in position for holding the runner, the head being thereby limited in its outward motions and prevented from projecting to too great extent from the stick.

It will be seen that the retainer may be fitted 60 in the kerf in the stick by inserting or driving the spur D longitudinally into the wall at one end of said kerf, then pressing the plate into the kerf, and driving the spur E laterally into the solid part of the stick opposite to the 65 spur D, whereby the retainer is firmly held in position. The head A' may now be pressed into the kerf to permit the passage of the runner, and when the head is let go it springs outwardly, owing to the shank B, and thus 70 holds the runner.

For hollow sticks, a pin or rivet may be driven through the stick and plate C to prevent displacement of the retainer.

Having thus described my invention, what 75 I claim as new, and desire to secure by Letters Patent, is—

1. A retainer for the runner of an umbrella or parasol, formed of a head, an elastic shank carrying the same, and a back plate with 80 which said shank is connected, said plate having at one end a longitudinally-extending spur which catches longitudinally in the stick, substantially as described.

2. An umbrella or parasol retainer formed 85 of a single piece of metal, having a back plate provided with both horizontal and vertical spurs, all substantially as described.

3. A retainer for the runner of an umbrella or parasol, consisting of a back plate having 90 the projecting stop G, with shoulder G', a shank with head having a shoulder adapted to engage with the said shoulder G', all substantially as described.

4. The back plate with the stop G, and the 95 head with a slot, H, and stop F, substantially as described.

W. H. WHARTON.
